UNITED STATES PATENT OFFICE.

PATRICK J. MONAHAN SULLIVAN, OF WOODCLIFFE-ON-HUDSON, NEW JERSEY,
ASSIGNOR TO MONAHAN ROTARY ENGINE CORPORATION, OF NEW YORK,
N. Y., A CORPORATION OF NEW YORK.

INTERNAL-COMBUSTION ENGINE.

1,274,812.

Specification of Letters Patent. Patented Aug. 6, 1918.

Application filed November 30, 1917. Serial No. 204,575.

To all whom it may concern:

Be it known that I, PATRICK JOHN MONAHAN SULLIVAN, a citizen of the United States, and resident of Woodcliff-on-Hudson, in the county of Bergen and State of New Jersey, have invented certain new and useful Improvements in Internal-Combustion Engines, of which the following is a specification.

10 This invention is an improvement in internal combustion engines of that type in which a piston and a cylinder have a relative back and forth movement, the piston being connected to a rotary crank. The ordinary engine of this type has the cylinder stationary and the piston mounted to reciprocate therein, the latter having a connecting or piston rod pivoted thereto for transmitting power to the rotary crank shaft. In such engines, it is difficult to keep the stationary cylinder properly cooled except by a water jacket and water circulating and cooling system; a large amount of energy is lost and objectionable jarring, straining and wear is produced by the bringing of the piston to a complete stop at each end of every stroke; and the transfer of power from the piston to the crank or vice versa, through the piston rod while the latter is at an angle to the direction of travel of the piston, produces a side thrust on the piston and objectionable frictional resistance and wear on both the piston and cylinder walls.

30 The objects of my invention are to overcome these and other objections and, while utilizing common general forms of piston and cylinder, to eliminate side thrust of the piston in the cylinder, eliminate reciprocation of heavy parts, secure effective air cooling, reduce friction, wear and vibration or jar of the parts, permit of the use of parts of lighter and less expensive construction, avoid the necessity for a crank case and produce a simple and highly efficient engine.

I accomplish these and other objects by so mounting the piston and cylinder that they have bodily movements in opposite directions along overlapping circular paths while at all times maintaining their common axis in parallelism with an initial position. A preferred means for so mounting the parts and which involves an important part of my invention, includes three parallel shafts hav-

ing equal throw cranks, two of the cranks being rotatable at the same speed in the same direction and serving to bodily carry the cylinder while the other crank rotates at the same speed in the opposite direction and is connected to the piston. By properly gearing or otherwise connecting the shafts together, the desired relative directions and speed of rotation may be maintained and the crank pin of the third shaft maintained in such position that it intersects and is at right angles to the axis of the cylinder. Thus, the piston rod may be rigidly connected to the piston and the thrust imparted to or by the piston will be at all times solely in the direction of the axis of the cylinder rather than at an angle thereto through a pivoted piston rod as in the ordinary construction. As both the piston and the cylinder move, the diameters of the circles through which the cylinder and piston move will be only one-half the total effective stroke of the piston and thus the crank may have only one-half as great a throw as that of the ordinary engine with the same effective piston stroke. This reduction in the radius of the cranks very materially reduces the radial pull resulting from the action of centrifugal force on the cranks.

At no time in the cycle do the parts come to a standstill or suddenly change their direction of movement. They all move at a uniform speed in their respective arcs of equal circles without jar, pounding action or enormous stresses occurring in the ordinary engine.

Although my invention is applicable to a single cylinder engine, yet economy of weight and parts, as well as great increase in power, is effected by using a double-ended cylinder or connecting two cylinders together in axial alinement so that a single pair of crank shafts will support two working chambers and the third crank placed intermediate of the other two may be connected to a double-ended piston or two pistons rigidly connected. No crank case is necessary or desirable. It is only necessary to have a longitudinally extending slot between the two working chambers and through which the intermediate crank may be connected to the piston.

To permit of the employment of simple, small-diameter gears for connecting to

gether the several shafts, and to permit of a compact base or frame, the three shafts may be in a plane at right angles to the axis of the cylinder with the cranks of the two outer shafts connected to the double-ended cylinder or pair of aligned cylinders midway between the opposite cylinder heads. This is not an essential so far as the principle of operation is concerned as the two parallel cylinder supporting shafts may be mounted in various different positions in respect to each other, for instance, adjacent to the opposite cylinder heads with their cranks in journals on said cylinder heads, as shown and claimed specifically in my application Serial No. 180,490, filed July 14, 1917.

A further embodiment of my broad invention is shown and specifically claimed in my prior application Serial No. 148,057, filed February 13, 1917, in which embodiment the cylinders or working chambers are supported by the crank of only one of the three crank shafts while separate pistons operating in separate working chambers upon opposite sides of this crank are separately connected to the cranks of the other two shafts. The relative movements of the pistons and cylinders, the number of crank shafts and the main advantages secured are the same as in the construction shown and specifically claimed in my application Serial No. 180,490 and the construction described and specifically claimed in this application. I have reserved for the present application all of the generic claims to my broad invention and have presented in the other applications above referred to only such claims or definitions of alternative forms as are not applicable to the specific form hereinafter described.

In the accompanying drawings, to which reference is to be had, I have illustrated one embodiment of my broad invention which has been built and found to operate highly satisfactorily and which also involves certain subsidiary but important novel features of construction.

In these drawings,

Figure 1 is a side elevation of an engine constructed in accordance with my invention, portions thereof being broken away;

Fig. 2 is a top plan view;

Fig. 3 is a detail of the fuel conduit connection; and

Figs. 4 to 7, inclusive, are diagrammatic views showing the pistons and cylinders in the successive positions they take during one revolution of the crank-shafts.

The engine, as diagrammatically illustrated in Figs. 4 to 7 inclusive, includes a double-ended cylinder which may be considered as two cylinders 10 and 11 rigidly connected and in axial alinement. Therein is a double-ended piston which may be considered as two pistons 12 and 13 rigid in

respect to each other and connected by a connecting or piston rod 14 which may be a straight bar integral with, or rigid with, or pivoted to both pistons. For supporting the cylinders there is provided a plurality of shafts (here shown as two in number) 15 and 16 having equal-throw parallel cranks of a radius equal to one-quarter the total desired effective piston stroke. The shafts are supported and journaled in any suitable stationary bed or frame (not shown), and the cranks 17 and 18 thereof are journaled in bearings 19 and 20 rigid with the cylinders. These bearings are diagrammatically illustrated as being in brackets on diametrically opposite sides of the double-ended cylinder, intermediate of its ends, but, as will be apparent when the operation is considered, these bearings on the cylinder may be at opposite ends or at any other two spaced points. It will also be apparent that any number of shafts greater than two may be employed, it only being necessary that they shall have parallel axes and equal throw cranks and all rotate at the same speed in the same direction. In order to insure this equal speed and direction of rotation of the cylinder carrying shafts, any form of gearing or other connecting means may be employed.

The same bed or frame that carries the two shafts 15 and 16 carries a third shaft 21 having a crank 22 of the same throw as the cranks 17 and 18, but journaled to the connecting rod 14 intermediate of the ends of the latter instead of to the cylinders. This shaft has its axis parallel to the other shafts but is intended for rotation in the opposite direction and this opposite direction of rotation may be insured by any suitable form of gearing or connecting means between the shaft of one or all of the other shafts.

In Fig. 4, the parts are shown at the end of one stroke. As the three shafts rotate, (the shaft 21 clockwise and the shafts 15 and 16 counter-clockwise) through a quarter of a revolution, the parts come to the position shown in Fig. 5. It will be noted that both the piston and the cylinder have had their common axis raised and that the piston has moved toward the right while the cylinder has moved toward the left. During the next quarter of a revolution of the shafts, the parts come to the position shown in Fig. 6 in which the piston is at the opposite end of its stroke.

In Fig. 7, the parts are shown in the positions which they occupy after the next quarter of a revolution and from this position they pass on to the position shown in Fig. 4.

The supporting of the cylinder and piston in this manner permits them to have bodily, planetary movements along circular paths in opposite directions while maintaining their axes at all times in parallelism with an initial position; every part moves in a true

circle; the relative reciprocation of the piston and cylinder is accomplished without bringing any parts to a dead stop at the end of a stroke; the cylinder is effectively air-cooled; and there is no side thrust of the piston on the cylinder.

So far as my broad invention is concerned, the engine may be of two, four or other number of strokes per cycle or the motive fluid 10 may be compressed air, steam, water or other fluid instead of explosive mixture. The construction may also be used as a pump or compressor. It is only necessary that suitable valves, valve operating mechanism 15 and supply and exhaust conduits be provided. The cranks which support the pistons and cylinders may be replaced by any equivalent mechanism, such as eccentrics, which will give the movements above described. The power may be taken from the engine through any one or through two or 20 more of the shafts and the engine may be balanced by a fly-wheel, or a plurality of cylinders may be mounted side by side on 25 separate oppositely extending cranks of the same shafts so that the movement of one double-ended cylinder and its piston will counter-balance the movement of another similar cylinder and piston.

30 It will also be evident that, so far as certain aspects of the invention are involved, one end of the double-ended cylinder and one end of the double-ended piston may be omitted so that there is provided only a single working chamber. The cylinder may have its axis extending vertically, horizontally or in any other desired direction.

In Figs. 1 and 2, I have shown a practical working embodiment of my invention. 40 The bed or frame of the engine includes two side members 23 and 24 each having a row of three superposed bearings for the three shafts 15, 21 and 16. Between the two and supported by the cranks 17 and 18 of the 45 shafts 15 and 16 are the two cylinders 10 and 11 and within the two cylinders are the pistons 12 and 13 connected by the rod 14 which latter is journaled on the crank 22 of the shaft 21. The movement and general 50 operation of these parts is the same as is diagrammatically illustrated in Figs. 4 to 7. The cylinder is shown as having radiating flanges to facilitate air-cooling and as having intermediate and exhaust puppet 55 valves of a common form. As an important part of the specific construction illustrated one of the cylinder supporting cranks, for instance, the crank 19, has a worm or helical gear 25 meshing with a helical gear 26 carried by a cam shaft 27 journaled in the bracket or extension 19 at one side of the cylinder. As both the crank 17 and the cam shaft 18 have their axis relatively movable 60 so far as the cylinder is concerned, it is evident that as the shaft 15 rotates the gears

will remain in mesh and that the cam shaft 27 will be caused to rotate about its own axis. The pitch of the gears should be such that, for a four cycle engine, the cam shaft rotates at one half the speed of revolution 70 as the shaft 15. This cam shaft may have a series of cams 28 thereon for engaging the push rods 29 of the several puppet valves. So far as the operation of the cams, push rods and valves are concerned, I may utilize 75 any type of construction commonly employed with four cycle engines having the usual stationary cylinder.

The explosive mixture may be formed in any suitable type of carburetor or other mixing device. This is preferably stationary and the conduit connections are such that the mixture is properly delivered from this stationary carburetor to the moving cylinders. As shown, a carburetor 31 is mounted 80 on the frame and delivers through a conduit 32 to a transversely extending sleeve 33 free to oscillate about the axis of the conduit to the cylinder intermediate of the ends and has branches 35 and 36 leading to the two 90 inlet ports. A conduit 37 is pivoted to the end of the manifold and is free to slide back and forth in the sleeve 33. Thus the manifold 34 may move in a true circle and the conduit 37 will have a movement similar to 95 that of the ordinary piston rod. The portion of said conduit 37 within the sleeve is provided with a series of perforations or is otherwise so constructed that the explosive mixture may enter the conduit 37 at all 100 times and independently of the relative positions of the manifold and carburetor. Although this fuel supply means possesses certain important advantages, yet it will be evident that other means might be designed 105 for accomplishing the desired results.

For effecting the ignition of the explosive mixture within the cylinders, any suitable form of igniting means may be employed. In the drawings, I have illustrated spark 110 plugs 40 of a common type of construction. The electric current may be delivered to these spark plugs through flexible wires although preferably I avoid the liability of a loosening of the connections of said wires 115 by providing the spark plugs with brushes 41 bearing against circular contact plates 42. These plates are preferably insulated from the frame of the machine and as they are stationary they may be readily connected to the source of electrical energy. The radius of each plate is substantially equal to the radius of the cranks so that the brushes 41 will remain in proper contact during the bodily movement of the cylinders. Each 120 plate may be of a single annular or circular piece of metal and the proper make-and-break contacts or timer may be in the portion of the electric circuit (not shown) or the plates themselves may be formed pri- 130

marily of insulation material with only a small portion constituting a conductor and in the electric circuit. Thus, the current will be delivered to the spark plugs only when the brushes 41 reach the conducting portion of their respective plates 42. By rotating the plates 42 about their axes, the time of the spark may be advanced or retarded.

10 Any suitable means may be provided for taking care of the exhaust gas. As shown, this is permitted to deliver directly to the atmosphere from the exhaust valves and their outlets 43. These may be connected 15 to a manifold and a delivery conduit similar to the manifold 34, its branches 35 and 36 and the conduit 37.

For insuring the simultaneous rotation of the three shafts 15, 16 and 21, with the 20 shafts 15 and 16 rotating in one direction and the shaft 21 in the opposite direction, suitable gearing may be employed for connecting said shafts. As shown, each of the 25 three shafts has a gear wheel 44, the three gear wheels meshing in series. The power of the engine may be taken from any one of the three shafts or, if desired, from all three. In Fig. 2 I have shown a belt pulley 45 and a fly-wheel 46. One of these may 30 serve the purpose of both if desired.

Having thus described my invention, what I claim as new and desire to secure by Letters Patent is:

1. In combination, a cylinder, a pair of 35 cranks rotatable about parallel spaced axes for supporting the same and maintaining it at all times in parallelism with an initial position, a piston within said cylinder, and a crank connected to said piston and rotatable in the opposite direction to said first mentioned cranks.

2. In combination, a cylinder, a piston, a pair of parallel cranks of equal throw for supporting said cylinder and permitting 45 bodily movement of said cylinder along a circular path and maintaining its axis at all times in parallelism with an initial position, a crank connected to said piston and having the same throw as the first mentioned cranks, and gearing connecting one of said first mentioned cranks and said last mentioned crank for insuring simultaneous rotation in opposite directions.

3. In combination, a double-ended engine 55 cylinder, means for imparting to said cylinder a bodily movement in respect to a transversely extending axis of rotation while retaining it in parallelism with its initial position, a piston within said cylinder, and means for imparting to said piston a bodily movement in the opposite direction in respect to an axis of rotation parallel to said first mentioned axis while retaining it in parallelism with an initial 60 position.

4. In combination, a plurality of cylinders in axial alignment and rigidly connected together, each cylinder having a working chamber at its outer end, separate pistons in said cylinders, means for moving said cylinders in respect to a transversely extending axis of rotation while retaining them in parallelism with an initial position, and means for moving said pistons in the opposite direction. 70

5. In combination, a double-ended cylinder, means for imparting a planetary movement thereto about one axis of rotation, a double-ended piston within said cylinder, and means for imparting a planetary movement to said piston about a different axis of rotation. 80

6. In combination, a double-ended cylinder, means for imparting a planetary movement thereto about one axis of rotation, a double-ended piston within said cylinder, and means for imparting a planetary movement to said piston about a different axis of rotation, said axes being parallel and extending transversely of the general direction of said cylinder and piston, and said piston and cylinder rotating in opposite directions. 90

7. In combination, a piston having a planetary movement in one direction and a double-ended cylinder having a planetary movement in the opposite direction. 95

8. In combination, a pair of rigidly connected cylinders, means for imparting a planetary movement thereto, a pair of 100 rigidly connected pistons within said cylinders, and means for imparting to said pistons a planetary movement in the opposite direction.

9. In combination, a pair of rigidly connected cylinders, a pair of rigidly connected pistons therein, means for imparting to said cylinders a bodily movement about a fixed transversely extending axis while retaining said cylinders in parallelism with an initial position, and means for imparting to said pistons a bodily movement about a separate, fixed, transversely extending axis while retaining said pistons in parallelism with an initial position. 105

10. In combination, a pair of rigidly connected cylinders, a pair of separate pistons therein, a pair of crank shafts having parallel axes and equal throw cranks, said cranks being connected to said cylinders to permit the bodily movement of the latter, and a third crank shaft having its crank connected to said pistons to permit a bodily and opposite movement of the latter. 110

11. In combination, three crank shafts 125 having parallel axes and equal throw cranks arranged in a row, a pair of cylinders in alignment with each other and rigidly connected and mounted on the cranks of the two end crank shafts, and a pair of pistons 120

within said cylinders and connected to the crank of the intermediate shaft.

12. In combination, three shafts arranged in a row and having equal throw cranks, a cylinder connected to and carried by the cranks of the two end shafts and a piston connected to the crank of the intermediate shaft.

13. In combination, three crank shafts arranged in a row and having equal throw cranks, a cylinder connected to and carried by the cranks of the two end shafts, a piston connected to the crank of the intermediate shaft, and means insuring the simultaneous rotation of the two end shafts in the same direction and the simultaneous rotation of the middle shaft in the opposite direction.

14. In combination, three crank shafts arranged in a row and having equal throw cranks, a cylinder bodily carried by the cranks of two shafts, and a piston connected to the crank of the third shaft.

15. In combination, three crank shafts arranged in a row and having equal throw cranks, a cylinder bodily carried by the cranks of two shafts, a piston connected to the crank of the third shaft, and means for insuring the rotation of the two cranks in one direction and the third crank in the opposite direction.

16. In combination, a cylinder, a piston therein, means for supporting said cylinder and permitting of a bodily planetary movement and maintaining its axis in parallelism with an initial position, means for supporting said piston and permitting of a bodily planetary movement in the opposite direction, an igniter carried by said cylinder, and means for delivering current to said igniter, said means including a pair of contacts, one in the form of a brush and the other in the form of an annular plate.

17. In combination, a cylinder, a pair of cranks rotatable about parallel spaced axes for supporting the same and maintaining it at all times in parallelism with an initial position, a valve operating cam shaft carried by said cylinder, and gearing connecting said cam shaft and one of said cranks.

18. In combination, a cylinder, means including a crank for supporting said cylinder, and effecting the bodily movement thereof with said crank during the rotation of the latter, a shaft carried by said cylinder, gearing connecting said shaft and said crank, and valve operating mechanism controlled by the rotation of said shaft.

19. In combination, a piston having a planetary movement in one direction, a double-ended cylinder having a planetary movement in the opposite direction, a valve operating cam shaft carried by said cylinder, and means for rotating said shaft about its axis during the bodily movement of said cylinder.

20. In combination, a double-ended cylinder having a planetary movement with its axis maintained in parallelism with an initial position, a supply manifold extending lengthwise of said cylinder and connected to opposite ends thereof, a stationary carbureter, and a conduit having one end connected to said manifold and movable along a circular path and having the opposite end slidably connected to said carbureter.

Signed at New York, in the county of New York, and State of New York, this 26th day of November, A. D. 1917.

PATRICK J. MONAHAN SULLIVAN.
